UNITED STATES PATENT OFFICE.

JOSEPH A. MILLER, OF HOPEDALE, MASSACHUSETTS, ASSIGNOR TO DRAPER CORPORATION, OF HOPEDALE, MASSACHUSETTS, A CORPORATION OF MAINE.

BOBBIN-CLUTCHING MEANS FOR ROTATABLLE SPINDLES.

Application filed September 17, 1926. Serial No. 136,044.

This invention relates to that type of spindle employed in spinning frames and similar machines in which bobbin clutching members are provided to fit within the base of the bobbin and to expand therein thus to maintain the bobbin in position during the spinning or other operation.

It is the object of the present invention to provide a simple and efficient form of construction which may be readily and economically manufactured, which will be subject to as little wear as possible, in which there shall be no parts likely to be broken or injured under the conditions to which the mechanism is subject in use, in which the pressure of the bobbin-clutching members shall be exerted symmetrically and evenly radially of the spindle, in which there shall be no sliding parts and in which the presence of lint or fly will not impair its operation.

These and other objects and features of the invention will appear more fully from the accompanying description and drawings and will be particularly pointed out in the claims.

As the general construction and operation of spinning and similar spindles with bobbin clutching members are well known and familiar to those skilled in the art, it will only be necessary here to illustrate and describe the parts directly concerned with the present invention. It will be recognized that spindles operate at a very high rate of speed, are subject to the collection of more or less lint and fly thereon, and that the operation of placing and doffing the bobbins is performed by more or less careless operators. The construction must be such that the bobbin may be readily placed on and doffed from the spindle and at the same time the construction must be such that the bobbin will be securely gripped and held whenever the spindle is rotated. This and the other conditions familiar to those skilled in the art render the bobbin clutching feature of the spindle one of the greatest importance and one to which a great deal of inventive ability has been directed.

50 In the drawings:

Fig. 1 is a side elevation of a portion of a spindle embodying a preferred form of the present invention.

Fig. 2 is a view chiefly in vertical cross

section on a much enlarged scale of the 55 construction shown in Fig. 1 with but one of the bobbin clutching members in place and with the parts in the position assumed when the bobbin is doffed.

Fig. 3 is a view similar to Fig. 2 with the 60 bobbin clutching member forced to the inward limit of its movement.

Fig. 4 is a side elevation of one of the bobbin clutching members such as shown in the preceding figures when in the position shown 65 in Fig. 2.

Fig. 5 is a side elevation of one of the bobbin clutching members such as shown in the preceding figures when in the position shown in Fig. 3.

70 Fig. 6 is a top plan view corresponding to Fig. 5.

Fig. 7 is a top plan view of the washer shown in Figs. 2 and 3.

Fig. 8 is a side elevation of a slightly 75 different form of bobbin clutching member standing in the unclutched or open position.

Fig. 9 is a view in vertical cross section of the construction shown in Fig. 8.

Fig. 10 is a view in side elevation of the 80 bobbin clutching member shown in Figs. 8 and 9 and standing in its innermost or vertical position.

Fig. 11 is a view in vertical cross section of the construction shown in Fig. 10.

85 In the preferred construction illustrated, the blade 1 of the spindle is of the usual form and has rigidly secured thereto, preferably by being driven tightly thereon, a whirl 2 of the usual type. This whirl has 90 rigidly secured thereto, preferably by a driving telescoping fit, a whirl cap 3 which preferably presents an upper flat surface 4 to receive the bobbin so that this cap itself 95 preferably constitutes the bobbin rest. In the construction illustrated, the whirl cap 3 surrounds and telescopes the upper end of the whirl and has a driving fit along the cylindrical surface 5.

The whirl is provided with an annular, 100 and preferably flat, surface 6 extending transversely of, and surrounding, the blade 1 and preferably located below the top of the whirl so as to form the bottom of an annular recess in the upper end of the whirl 105 concentric with the spindle blade.

The bobbin clutching members are all of exactly similar construction and are dis-

posed symmetrically around the spindle blade. Any required number may be employed, but three has been found to be practical and successful. In the detail figures of the drawing, one of these bobbin clutching members is illustrated. This bobbin clutching member comprises an arm 7 having the cross section of a sector of a cylinder and extending up alongside the spindle. At its 10 extreme upper end the arm is curved inwardly at 8 to form a surface over which the bobbin may readily be slipped. At its upper portion the arm is formed at 9 to present an upwardly projecting flange 10 cooperating with a depending flange 11 of a ferrule 12 driven on or secured to the blade 1. The cooperating flanges 10 and 11 limit the outward movement of the arms. This is a common feature of construction. 20 The formation of the arm at the portion 9 serves also to weight the arm and thus to increase the clutching action of the arm due to centrifugal force when the spindle is rotated. At its lower end the arm is provided with a sector-shaped foot 13 projecting outwardly from the arm and at an acute angle thereto.

The feet of the bobbin clutching members are seated on the surface 6 of the whirl and 30 the bobbin clutching members are preferably maintained in symmetrical spaced relation by spacing pins 14 driven into the whirl.

The whirl cap or bobbin rest 3 is provided with an annular depending flange 15 located 35 above, and spaced from, the feet 13 and extending between the arms 7 and the outer periphery of the feet. Preferably each foot at or near its outer periphery is provided with an upwardly projecting rib 16, which 40 also extends concentrically of the blade 1 and consequently of the flange 15.

A resilient washer formed of suitable resilient metal is mounted between the whirl cap or bobbin rest and the feet of the bobbin clutching members. This washer, as shown 45 in Figs. 2 and 3, and in Fig. 7, is preferably of concavo-convex form with the concave surface 17 uppermost. This washer engages on concentric lines the bottom of the flange 15 and the outer portions, or the rib 16, of the feet 13. The concave face 17, in the construction illustrated and preferably, engages the flange 15 on the whirl cap or bobbin rest and the convex face 18 engages the outer 50 portion or the rib 16 on the feet of the bobbin clutching member.

The parts thus described are assembled and driven together so that the resiliency of the washer reacting on an inner concentric line against the bottom of the flange 15 and on an outer concentric line against the outer portions or the rib 16 of the feet acts to force the outer portions of the feet downwardly and consequently the upper ends of 60 the bobbin clutching arms radially outward

from the blade. This effect is produced by the distortion or resilient action of the washer.

In the construction illustrated in the first six figures of the drawing, the bottom surfaces 19 of the feet, as best seen in Fig. 5, present sectors of a common frusto-conical surface. Theoretically, therefore, such a bobbin clutching member rocks between the positions shown in Figs. 2 and 3 on a point 70 20 at the middle of the inner curved edge of the foot.

In the construction illustrated in Figs. 8 to 11, inclusive, the bobbin clutching members are of the same general construction as 80 already described comprising the arms 21 and the feet 22, but in this case the bottom surfaces 23 of the feet are flat. In this construction, theoretically, the segments in swinging between the extreme positions rock 85 on the two end corners 24 of the inner curved edge and each member, when in its outermost position, as shown in Figs. 8 and 9, has the bottom surface of the foot seated throughout on the surface of the whirl.

In either of the constructions illustrated, the force due to the distortion of the washer, which may be either in distorting it from its generally flat form or restoring it from a distorted form to its generally flat form, is 90 the main force utilized in swinging the bobbin clutching members radially outward, but in addition, when the spindle is running, the force due to centrifugal action comes into play to augment the clutching action 100 and this centrifugal force is increased because of the weighted upper portions of the bobbin clutching arms.

Having thus described the invention, what is claimed as new, and desired to be secured by Letters Patent, is:

1. A rotatable spindle comprising a blade, a whirl secured to the blade, and presenting an annular surface transversely of, and surrounding, the blade, a plurality of bobbin clutching members each having an arm extending up alongside the blade and a sector-shaped foot projecting outwardly from, and at an acute angle to, the arm and seated on said annular surface, and an annular whirl cap surrounding and spaced from said arms secured to the whirl, and having an annular depending flange located above, and spaced from, the feet between the arms and the periphery of the feet, and a resilient washer engaging on concentric lines the bottom of said flange and the outer portions of said feet, the resiliency of the washer reacting against the flange and the outer portions of said feet to force the upper ends of the bobbin clutching arms radially outward from the blade.

2. A rotatable spindle comprising a blade, a whirl secured to the blade, and presenting an annular surface transversely of, and sur-

- rounding, the blade, a plurality of bobbin clutting members each having an arm extending up alongside the blade with the upper portion thereof weighted to increase 5 the clutting action due to centrifugal force and each having a sector-shaped foot projecting outwardly from, and at an acute angle to, the arm and seated on the said annular surface, the outer portions of the 10 said feet being each provided with an upwardly projecting rib extending concentrically of the blade, an annular whirl cap surrounding and spaced from said arms and secured to the whirl and having an annular 15 depending flange located above and spaced

from the feet between the arms and the upwardly projecting rib on the feet, and a resilient washer of concavo-convex form having its concave face engaging the depending flange on the whirl cap and its convex face 20 engaging the upwardly projecting rib on the feet on concentric lines, the resiliency of the washer reacting against the said depending flange and the said upwardly projecting rib to force the upper ends of the bobbin clutching arms radially outward from the blade. 25

In testimony whereof, I have signed my name to this specification.

JOSEPH A. MILLER.
